FREE SERVICE COIN-CONTROLLED
MACHINE

Harry S. Benjamin, Poughkeepsie, N. Y.

Application December 26, 1940, Serial No. 371,700

1 Claim. (Cl. 194—57)

This invention relates to coin-controlled machines, and, in particular, to machines wherein the operator is permitted to obtain intermittent free-service from the machine.

One object of this invention is to provide a coin-controlled machine wherein means is provided for enabling the operator to operate the machine for a "free" operating cycle after a predetermined number of paid operating cycles have been carried out by the machine.

Another object is to provide a coin-controlled machine having means for retaining the coin of the operator but permitting the carrying out of an additional "free" operating cycle after a predetermined number of paid operating cycles have been performed, thereby enabling the operator to obtain free merchandise or a free cycle of operation of the machine.

Another object is to provide a coin-controlled machine wherein means is provided for enabling the operator to carry out a complete working cycle without using a coin after a predetermined number of paid working cycles has been effected, thereby enabling the operator to obtain free merchandise or otherwise benefit as the result of obtaining a "free" working cycle after a predetermined number of working cycles have been paid for.

Another object is to provide a coin-controlled machine of the type set forth in the preceding objects wherein signalling means is provided for notifying the operator when a profit-sharing "free" working cycle has arrived.

The coin-responsive mechanism herein is disclosed and claimed apart from the profit-sharing mechanism, in my co-pending application Serial No. 359,755, filed October 4, 1940.

In the drawings:

Figure 1 is a side elevation of a preferred embodiment of the invention, with the operating bar in its upper or starting position.

Figure 2 is a front elevation of the mechanism shown in Figure 1.

Figure 3 is a view similar to the upper part of Figure 1, but showing the positions of the parts at the end of the down stroke in the final "paid" cycle immediately before a "free" cycle of operation.

Figure 4 is a view similar to Figure 3, but showing the positions of the parts at the top of the return stroke of the operating bar at the end of the final "paid" cycle of operation just prior to the "free" cycle.

Figure 5 is a view similar to Figures 3 and 4, but showing the positions of the parts at the com-

mencement of the "free" cycle just after the completion of the final "paid" cycle of Figure 4.

Figure 6 is a horizontal section along the line 5 6—6 in Figure 1 showing the free-service mechanism in plane view.

Figure 7 is a vertical section through the free-service mechanism taken along the line 7—7 in Figure 2.

GENERAL ARRANGEMENT

In general, the coin-controlled machine of the invention is intended for use with vending machines or other coin-operated machines intended to perform services or provide amusement 15 for the operator. In the machine of the present invention, the coin is deposited in a position where it is supported by three rollers mounted on three separate levers. These rollers are operatively connected or related to an operating 20 bar which is set in motion when the operator turns the operating knob or moves an operating member corresponding to the operating knob.

The operating bar is provided with various cams which actuate the coin roller levers in various 25 ways. After a coin has been inserted and a partial operating cycle has been accomplished, the operator may change his mind and get his coin back if he releases the operating knob or other operating member. In that event, the mechanism moves one or more of the coin holding rollers to permit the coin to fall into the coin return chute whereby it is returned to the operator. If, however, the operator continues the operating cycle beyond this predetermined point, 30 the mechanism prevents the return of the coin and carries out the complete operating cycle, thereby guiding the coin into the coin box and ejecting the mechanism or performing the service for which the coin was deposited. In this event, one of the coin holding rollers moves in a different direction to guide the coin into the coin box rather than into the coin return chute, as in the partial cycle where the operator changed his mind and sought the return of his coin.

The machine of the present invention also permits a partial stroke or cycle when no coin whatever has been deposited therein. This enables the machine to be cleared of slugs, false coins, or coins of the wrong denominations.

The machine is also provided with a so-called free-service device, whereby the operator obtains a "free" working cycle of the machine after a predetermined number of operating cycles have been paid for. This free-service device is accompanied by a signalling device, such as a bell,

which notifies the operator of the arrival of a "free" working cycle. In particular, the free-service device consists of ratchet mechanism which holds out of operation the latching mechanism which ordinarily prevents the completion of a working stroke without the use of a coin.

A modification of the invention provides an intermittent free service machine wherein a coin other than the coin deposited by the operator is returned to the operator as the result of the operation of the profit-sharing mechanism. Other modifications provide different mechanisms for effecting the free-service cycles.

Construction of coin-controlled machine

Referring to the drawings in detail, Figure 1 shows a preferred embodiment of the coin-controlled machine of the invention as consisting of a frame 20 having a plate 21 secured thereto, as by the flange portion 22 and screws 23. The plate 21 projects forwardly from the frame 20 and has secured thereto, as at 24, a second plate 25. The two plates 21 and 25 are placed face to face with each other and are held closely together.

Secured as at 26 to the plate 21 is a coin chute 27 aligned with a coin slot 28 in a coin window 29 mounted in the front wall 30 of the machine. The coin chute 27 is inclined downwardly and consists of a generally inclined portion 31 and a vertical portion 32. The vertical portion 32 terminates immediately above a closure member 33 secured as at 34 to the plates 21 and 25. The closure member 33 is spaced apart from the plate 21 by a space sufficient for the passage of a coin, and for that purpose (Figure 3), it is provided with flanged front and rear walls 35 and 36 respectively. The retaining member 33 is bifurcated in its lower parts, and is there provided with a coin retaining chute 37 near the front of the machine and a coin returning chute 38 at the rear thereof. The division between the two chutes 37 and 38 is made by means of the inclined flanged inner walls 39 and 40 respectively, so that a coin which falls upon the inclined wall 39 is guided downwardly into the coin box and is retained by the machine, whereas a coin falling upon the inclined flange 40 is guided downwardly into the coin return chute 38 and is returned to the operator.

The closure member 33 at its upper end is provided with a coin inlet port 41 (Figure 1) communicating with the lower end of the vertical portion 32 of the coin chute 27. For purposes of simplicity, the coin chute 27 is shown as leading directly into the chamber 42 (Figure 1) within the closure member 33. In actual practice, however, the machine is additionally provided with so-called coin-testing mechanism interposed between the coin chute 27 and the subsequent mechanism, whereby slugs, washers, buttons, coins of the wrong denominations, and other improper checks or coins are eliminated, thus permitting only proper coins or checks to pass into the chamber 42 within the closure member 33. This coin testing mechanism is well known to those skilled in the art, and forms no part of the present invention.

After passing downwardly through the passages 31 and 32 of the coin chute 27, the coin 43 comes to rest upon a bottom coin-holding roller 44 and against either the front coin-holding roller 45 or the rear coin-holding roller 46. The bottom coin-holding roller 44 is rotatably

mounted upon a pin 47 (Figures 3 and 4) mounted in the upper end of the bottom roller lever 48. The latter at its upper end is provided with a projection 49 and at its mid-point is provided with a second projection 50 adjacent the pivot pin 51 upon which the bottom roller lever 48 is pivotally mounted and which in turn is mounted in the vertically reciprocable operating bar 52. The lower end of the bottom roller lever 48 is provided with a pin 53 to which is secured one end of a spring 54, the opposite end of which is secured to a pin 55 mounted near the lower end of the operating bar 52.

The rear coin-holding roller 46 is rotatably mounted upon a pin 57 mounted at the mid-portion of the rear roller lever 58, the lower end of which is pivotally mounted upon the pivot pin 59 secured to the plate 25 (Figures 1 and 3). The upper end of the lever 58 is provided with a head 60 carrying a projection or cam follower 61 which engages the cam portion 62 of the lower operating bar cam 63. The cam 63 is fixedly secured to the operating bar 52 and serves to control the motion of the rear coin roller lever 58 as the operating bar 52 is moved downward by the operator or upward by a coil spring 64 anchored as at 65 to the plate 25, and at its opposite end secured to the member 66 attached as at 67 to the lower end of the operating bar 52 (Figure 1). The cam follower portion 61 is urged against the cam portion 62 (Figure 1) by means of the coil spring 68 secured as at 69 to the head 60 of the lever 58 and at its opposite end to the pin 70 mounted on the operating bar 52.

The front roller 45 (Figure 1) is rotatably mounted upon a pin 71 which in turn is mounted at the upper end of the front coin roller lever 72. The latter is in bell crank form, and is pivotally mounted upon the pivot pin 73 mounted on the plate 25 (Figure 1). The upper arm 74 of the front roller lever 72 carries an ear 75 to which one end of a spring 76 is attached, the other end being connected to an ear 77 upon the front cam lever 78. The lower arm 79 of the front roller lever 72 is provided at its end with a pivot pin 80 (Figure 1) carrying a roller 81 adapted to be engaged by the projection 49 of the bottom coin roller lever 48 when the latter is swung in that direction on the return stroke of the operating bar 52 by the engagement of the upper edge of its projection 50 with the lower edge of the nose 82 of the yieldable tripping lever 83 (Figure 1) of bell crank form mounted upon the pivot pin 84 secured to the plate 25. The lower end of the tripping lever 83 is provided with an ear 85 to which one end of a spring 86 is secured, the opposite end being secured to a pin 87 mounted on the operating bar 52. On the downward stroke of the operating bar 52, the projection 50 on the bottom roller lever 48 engages the nose 82 and pushes the trip lever 83 forwardly away from the stop pin 88 and moves on to engage the pin 89. This causes the bottom roller lever 48 to swing rearward, dropping any coin then resting on the bottom roller 44 into the chute 37 and thence into the coin box of the machine. If this downward stroke is halted and the upward or return stroke commenced after passing the tripping lever 83 but before reaching the pin 89, however, the engagement of the projection 50 with the nose 82 of the now unmoving tripping lever 83 causes the bottom roller lever 48 forward so that its upper projection 49 engages the roller 81 of the front roller lever 72 and swings the latter rearward. This causes any coin then resting on the

Figure 1. It consists broadly of a ratchet operated stop which rings a bell or operates any other suitable signalling device when the intermittent free-service cycle has arrived, and at the same time engages the pin 100 on the upper end of the cam lever 78 and holds it in its forward position, so as to permit the machine to be operated for a complete working cycle without a coin, thus delivering an additional article of merchandise to the operator for a single coin.

For this purpose the pivot pin 51 of the bottom roller lever 48 carries a roller 160 which engages the bifurcated ends 161 and 162 of a lever 163 pivoted upon a pin 164 mounted on the plate 25. The upper end of the lever 163 carries a pin 165 which enters and moves in a slot 166 within an arm 167 forming an extension of the pawl-carrying member 168. The latter is provided with an ear 169 to which is secured one end of a spring 170, the opposite end of which is attached as at 171 to a pawl 172. The pawl 172 is pivotally mounted on the pin 173 secured to the pawl-carrying member 168. The spring 170 urges the pointed tip 174 of the pawl 172 into engagement with the teeth 175 of a ratchet pinion 176.

The pawl-carrying member 163 and the ratchet pinion 176 rotate around a pivot pin or pindle 177 mounted in the plate 25. The rearward rotation of the ratchet pinion 176 is prevented by a retardation pawl 178 pivoted upon the pin 179 mounted on the plate 25 and having an ear 180 to which one end of a spring 181 is secured, the opposite end being anchored to a pin 182 mounted on the plate 25. This spring 181 urges the tip 183 of the retardation pawl 178 into engagement with the ratchet teeth 175.

Also mounted on the pivot pin 177 and rotatable therearound is a cam disk 184 having a cam slot 185 in the periphery thereof. The cam disk 184 is connected to the ratchet 176 and rotates as a unit therewith.

Also pivoted upon the pivot pin 179 is a lever 186 having an aperture 187 at the center thereof for providing clearance relatively to the pivot pin 177. The lever 186 is provided with a projecting arm 188 carrying a pin 189 (Figure 1) adapted to enter the cam slot 185 when the latter arrives opposite the pin 189, thus permitting the lever 186 to drop under the action of a spring 190 secured at one end to a pin 191 mounted on an extension 192 of the plate 25 at its other end as at 193 to a projecting arm 194 integral with the lever 186 and providing a bell crank effect.

Secured to the arm as at 195 is a rod 196 carrying a bell clapper 197. The latter is adapted to hit and ring a bell 198 secured as at 199 to the plate extension 192 when the pin 189 enters the cam slot 185. The outer end of the lever 186 is provided with an abutment portion 200 adapted to engage and hold out the pin 100 on the front cam lever 78 when the pin 189 enters the cam slot 185 preparatory to a free-service cycle of operation.

Operation

The operation of the machine has already been indicated above in connection with the description of the various mechanisms. To operate the machine, the operator places a coin 43 in the coin slot 28, whence the coin passes downward through the coin chute 27 through the port 41 and halts when it falls upon two of the three rollers 44, 45 and 46 (Figure 1). As previously explained, the coin in an actual machine is checked for its proper value by testing mecha-

nism forming no part of the invention and omitted in order to simplify the showing. At the start the various parts occupy the positions shown in Figures 1 and 2.

The operator now rotates the knob 125 and as a consequence draws down the operating bar 52. As the bar 52 and its cam 63 move downward, the projections 61 and 91 on the levers 58 and 78 move inwardly over the top of the cam 63, permitting the coin-holding rollers 45 and 46 to be pulled toward one another by the springs 68 and 98, pushing the coin 43 downward. Meanwhile, the bottom coin-holding roller 44 has moved downward with the operating bar 52 and permits the front and rear rollers 45 and 46 to move over the top of the coin, holding the coin firmly between the three rollers. As the bar 52 moves downward, the projection 50 upon the bottom roller lever 48 engages the nose 82 of the tripping lever 83, pushes it aside, and passes beneath it with a click as the tripping lever 83 returns to its original position.

If the operator now changes his mind and decides that he wishes a different article of merchandise from that which he originally selected, he can have his coin returned by merely releasing the knob 125. When this is done, the springs 130 and 64 return the parts to their original positions of Figures 1 and 2. In the meantime, however,

the operating bar 52 moves upward and the projection 50 on the bottom roller lever 48 engages the lower edge of the nose 82 on the tripping lever 83. Since the latter cannot swing, due to the presence of the stop pin 88, the lever 48 itself is swung toward the front of the machine and its projection 49 engages the roller 81 on the lower arm 79 of the front roller lever 72, swinging the front coin-holding roller 45 rearwardly as the bottom coin-holding roller 44 moves forwardly. At the same time, the rear roller lever 58 and the rear coin-holding roller 46 are moved rearwardly by the engagement of the projection 61 thereof with the cam 63. The coin 43, accordingly, drops through the gap between the oppositely moving coin-holding rollers 44 and 46 and is deflected by the flange 40 into the coin returning chute 38. The coin then falls into the merchandise delivery chute and is returned to the operator. The latter may then insert the coin in the coin chute corresponding to another kind of merchandise.

Let it be assumed, however, that the operator is satisfied with his choice, and rotates the knob 125 as far as it will go. When the shaft 122 has rotated the quadrant ratchet 135 to the point where the pawl arm 139 engages between the teeth 136 of the ratchet 135 (Figure 2), or just beyond the end of the "mind-changing" part of the cycle, the pawl 137 will prevent the return motion of the knob 125 until it has been completely rotated. As the operating bar 52 moves downwardly to the end of its stroke (Figure 5), therefore, the projection 50 on the bottom coin-holding roller lever 48 engages the fixed pin 89 and swings the lever 48 and the bottom coin-holding roller 44 rearward, opening a gap between

it and the forward coin-holding roller 45 through which the coin 43 drops downward into the coin retaining chute 37 and thence into the coin box of the machine. The front coin-holding roller 45 is permitted to move forward when the lever 78 is forcibly moved forward by the engagement of the pin 99 with the upper arm 98 of the bell crank lever 96, the lower arm 95 of which (Figure 5) engages the sleeve 94 and forces the lever 98 forward as the operating bar 52 approaches the

bottom roller 44 to be dropped into the coin return chute 38 and returned to the operator.

Also secured to the end 77 on the front cam lever 78 is one end of a spring 90, the opposite end of which is anchored to the pin 70 mounted on the operating bar 52. The lower end of the front cam lever 78 is pivotally mounted upon the same pivot pin 73 which pivotally supports the front roller lever 72. The mid-portion of the front cam lever 78 is provided with a projection or cam follower 91 (Figure 1) which engages the cam portion 92 upon the forward end of the cam 63 mounted on the operating bar 52. Adjacent the cam follower 91 on the front cam lever 78 is an adjusting screw 93 carrying a non-rotatable eccentric sleeve 94 (Figure 1) which is engaged by the lower arm 95 of a bell-crank lever 96 pivotally mounted upon the pin 97 secured to the plate 25 and having its upper arm 98 engageable by a pin 99 mounted on the upper end of the operating bar 52. When the operating bar 52 nears the lower end of its operating stroke, but beyond the point where the operator may change his mind and have his coin returned, the pin 99 engages the upper arm 98 and swings the lower arm 95 of the bell crank lever 96 forwardly against the sleeve 94, swinging the front cam lever 78 forwardly and likewise permitting the front roller lever 72 to swing forwardly under the influence of the coil spring 76. By loosening the adjusting screw 93, the eccentric sleeve 94 may be rotated to a different position and then secured in this position by tightening the screw 93. This enables the motion of the front cam lever 78 to be properly synchronized with the operation of the remainder of the mechanism.

The upper end of the front cam lever 78 carries a stop pin 100 which is adapted to swing beneath the cross member 101 fixedly secured to the operating bar 52 near its upper end. This arrangement halts the operating bar 52 at a predetermined position when the machine is attemptedly operated without a coin. The motion of the operating bar 52 as a whole is guided and also limited by slots 102 and 103 near its opposite ends and serving to receive pins 104 and 105 mounted in the upper and lower portions respectively of the plate 25.

The plate 21 along its lower edge is provided with slightly bent, coin-deflecting portions 106 and 107 cooperating with the adjacent portions of the closure member 33 to deflect the coin either into the coin return chute 38 or into the coin-retaining chute 37 as the case may be. The plates 21 and 25 are formed with elongated apertures or slots 108, 109 and 110 for respectively permitting the motion of the coin-holding rollers 44, 45 and 46 as well as permitting the rollers to project therethrough into the chamber 42 formed between the plate 21 and the closure member 33 (Figure 2).

Operating mechanism

The operating bar 52 may be reciprocated in any desired manner by any suitable operating member manipulated by the operator. For purposes of illustration, the machine is shown as provided with actuating mechanism similar to that disclosed in United States Letters Patent No. 2,010,911 to H. S. Benjamin, dated August 13, 1935, for a Vertical column vending machine. Reference is made to this patent for a vending machine to which the coin-controlled machine of the present invention may be attached for vending articles such as candy, gum, food, etc.

For this purpose a link 111 (Figures 1 and 2) is

provided with an ear 112 pivotally mounted upon the screw 67 in the lower end of the operating bar 52. The link 111 is slotted as at 113 to receive a guide pin 114 mounted in the supporting plate 115. The supporting plate 115 is secured as at 116 to the forward flange 117 of the angle plate 118 (Figure 1), the rearward flange 119 of which is secured as at 120 to the frame or rear wall 20. The latter is provided with a hole 121 in which is journaled an operating shaft 122, the forward end of which is journaled in an aperture 123 in the front wall 115, and is provided with an operating knob 125 mounted thereon. The operating knob 125 is the external part which is grasped by the operator for operating the machine.

Mounted on the operating shaft 122 is a cam 126 (Figure 1) of roughly triangular shape and arranged to engage a roller 127 mounted on a pin 128 carried by the lower end of the link 111. The latter is slotted as at 129 (Figure 2) in order for it to accommodate the operating shaft 122. As a consequence, when the knob 125 is rotated, and with it the cam 126, the engagement of the cam follower roller 127 with the cam 126 causes the link 111 and operating bar 52 to be drawn downward. When the knob 125 is released, however, the spring 64 assists in retracting the operating bar 52 and link 111. At the same time, however, the knob 125 and operating shaft 122 are returned to their original position by means of a spring 130 secured at one end to the pin 131 mounted in the supporting plate 115 and at its other end passing over a circumferential groove 132 in a disk 133 mounted on the operating shaft 122 and anchored by the screw 134 (Figure 1).

Also mounted on the operating shaft 122 is a quadrant ratchet 135 resembling a mutilated gear and having ratchet teeth 136 extending only partially around its periphery. The ratchet teeth 136 (Figures 1 and 2) are engageable with a bell crank pawl 137 mounted on the pivot pin 138 secured to the supporting plate 115. One arm 139 of the bell crank pawl 137 is formed and positioned to engage the ratchet teeth 136 whereas the other arm 140 is connected to one end of a spring 141, the other end of which is anchored to the pin 142 mounted on the supporting plate 115.

In order to effect the vending of the merchandise, the shaft 122 is provided with an additional cam 143 mounted thereon and engageable with roller 144 mounted on pin 145 which in turn is secured to the vending member 146. The latter is slotted as at 147 to accommodate the shaft 122 and at its lower end is provided with a pin 148 to which is secured a spring 149 having its opposite end anchored to the pin 150 mounted on the frame or rear wall 20. The spring 149 constantly urges the roller 144 against the periphery of the cam 143. The vending member 146 extends upward into the interior of the machine and accomplishes the service for which the operator deposited his coin. In particular, if the machine is a vending machine, the vending member 146 operates a releasing device which releases the article of merchandise, as more fully disclosed in the previously mentioned Benjamin patent No. 2,010,911 of August 13, 1935. The particular form of this vending mechanism forms no part of the present invention.

Intermittent free-service mechanism

The intermittent free-service mechanism is located chiefly in the upper left-hand corner of

end of its working stroke. This still further widens the gap between the bottom roller 44 and the front roller 45.

While this is occurring, the rotation of the operating shaft 122 rotates the cam 143 (Figure 1) and pulls down the vending member 146, releasing an article of merchandise in the manner set forth in the previously mentioned Benjamin Patent No. 2,010,911 of August 13, 1935. The article thus vended drops down through the vending chute and is withdrawn by the operator. By this time the pawl arm 139 has passed over all of the teeth 136 of the quadrant ratchet 135.

When the knob 125 is released, therefore, the spring 138 acting on the disk 133 rotates the operating shaft 122 and knob 125 backward to their starting positions, while the pawl arm 139 clicks over the ratchet teeth 136 until the ratchet 135 reaches its starting position (Figure 1). Meanwhile, the upward motion of the cam 63 on the operating bar 52 forces the levers 58 and 78 apart and causes the front and rear rollers 45 and 46 to move apart from each other, ready for the reception of another coin.

In case the knob 125 is rotated without the depositing of a coin in the coin chute 31, the machine operates through a part of the operating cycle in the manner previously described. This partial operation enables the machine to be cleared of slugs, buttons, washers or other undesirable articles. As the operating bar 52 moves downward, the projection 91 on the lever 78 moves over the top of the cam 63 and permits the lever 78 to move rearward, causing the pin 100 on the end thereof to move beneath the cross member 101 on the operating bar 52. This action effectively halts the downward motion of the operating bar 52, and accordingly prevents the rotation of the knob 125 to a position where it will vend merchandise.

Meanwhile, the free-service mechanism has been in operation. Upon each reciprocation of the operating bar 52, the lever 163 is swung through an arc by its engagement with the roller 160 (Figure 1), causing its end pin 165 to swing to and fro in the slot 166. This action causes the pawl-carrying member 167 to oscillate around the pin 177, each oscillation causing the pawl 172 to advance the ratchet 176 by one tooth. The ratchet 176 is prevented from rotating during the return stroke of the operating bar 52 by reason of the action of the retardation pawl 178.

After a predetermined number of "paid" working strokes have been accomplished, depending upon the number of ratchet teeth 175 in the ratchet pinion 176, the cam disk 184 is rotated until its cam slot 185 arrives at a location immediately beneath the pin 189 on the arm 188 of the lever 186. When this occurs, the pin 189 drops into the cam slot 185, permitting the lever 186 to swing downward and carry the abutment portion 200 into the path of the pin 100 upon the end of the front cam lever 78 (Figure 3). At the same time, the clapper 197 rings the bell 198, warning the operator that he is now entitled to receive an additional working stroke of the machine and obtain an additional article of merchandise without the necessity of depositing an additional coin.

To obtain the additional merchandise, the operator rotates the knob 125 as before and the operating bar 52 moves downward as usual. Since there is no coin in position between the coin-holding rollers 44, 45 and 46, the front cam lever 78 moves inward as usual to place the stop pin

100 beneath the cross member 101 on the operating bar 52 and halt the latter before it has completed a down stroke. Before the stop pin 100 reaches this position, however, it is intercepted by and encounters the abutment portion 200 of the lever 186, so that the operating bar 52 is not prevented from moving to the end of its downward stroke as in the ordinary operation of the device. The operator is thus permitted to rotate the knob 125 to the end of a working stroke and obtain an additional or "free" article of merchandise without having placed an additional coin in the coin slot 28.

As the bar 52 moves downward upon its "free" working stroke, that is, without a coin, it operates the pawl 172 through the lever 163 as before, and advances the ratchet 176 by another tooth. This action rotates the cam disk 184 through an additional distance equivalent to one ratchet tooth, causing the cam slot 185 to pass out from underneath the pin 189. As this occurs (Figure 5), the pin 189 is caused to climb the opposite side of the cam slot 185 and comes to rest again on the periphery of the cam disk 184, lifting the lever 186 and raising the abutment portion 200 out of the path of the stop pin 100.

If, now, the operator attempts to operate the machine for another working stroke without inserting a coin, the abutment 200 is no longer in position to intercept the stop pin 100. Accordingly, the stop pin 100 moves beneath the cross member 101 as the lever 78 swings inward in the manner previously described. This brings the operating bar 52 to a halt before the end of the working stroke has been accomplished, preventing the delivery of further merchandise until a coin has again been inserted.

The operator now releases the knob 125, whereupon the springs 64 and 130 cooperate to move the operating bar 52 upward to its return position (Figure 1). When the operating bar 52 is moved through the partial stroke permitted when there is no coin in the machine, the lever 163 is not shifted a sufficient distance to actuate the pawl-carrying member 167 far enough to move the ratchet 176. As a consequence the cam disk 184 is not rotated when the machine is operated without a coin, except during the full cycle permitted on the free-service stroke as described above. In this way the operator is prevented from advancing the cam disk 184 to the profit-sharing position merely by working the machine through a repeated number of the partial strokes permitted by the mechanism without the insertion of coins.

While I have shown and described my invention in detail, it is to be understood that the same is to be limited only by the appended claim for many changes may be made without departing from the spirit and scope of my invention.

What I claim is:

In a coin-controlled machine, coin-operated service-rendering mechanism, a movable machine-operating member, a plurality of levers having coin-holding portions thereon, one of said levers being mounted on and movable with said operating member, means responsive to the motion of said operating member for moving the other levers to maintain their coin-holding portions in engagement with the coin, and free-service means responsive to the completion of a predetermined number of paid operations of said machine for conditioning said service mechanism to render said service in the absence of a coin.

HARRY S. BENJAMIN.
